(57) **CLAIM**

The ornamental design for a space-saving computer keyboard layout, as shown and described.

DESCRIPTION

FIG. 1 is a top plan view of a space-saving computer keyboard layout showing our new design wherein the broken lines are shown for illustrative purposes only and forms no part of the claimed design;

FIG. 2 front elevational view thereof;

FIG. 3 is a rear elevational view thereof;

FIG. 4 is a left side elevational view thereof;

FIG. 5 is a right side elevational view thereof;

FIG. 6 is a reduced bottom plan view thereof;

FIG. 7 is a top front right side isometric view thereof.
